(57) **CLAIM**

The ornamental design for a two-legged portable target stand, as shown.

DESCRIPTION

FIG. 1 is an upper perspective view of the two-legged portable target stand in an open position showing my new design;

FIG. 2 is a lower perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof;

FIG. 9 is an upper perspective view of the two-legged portable target stand in a folded position;

FIG. 10 is a bottom perspective view of FIG. 9;

FIG. 11 is a top view of FIG. 9;

FIG. 12 is a bottom view of FIG. 9;

FIG. 13 is a left side view of FIG. 9;

FIG. 14 is a right side view of FIG. 9;

FIG. 15 is a front view of FIG. 9; and,

FIG. 16 is a rear view of FIG. 9.
